a corporation of Ohio
Filed Jan. 9, 1962, Ser. No. 68,240

Term of patent 14 years

(Cl. D49—1)

FIG-1

FIG-3

FIG-2

FIG. 1 is a perspective view of a commercial dishwashing machine, showing our new design;

FIG. 2 is a fragmentary perspective view from the opposite front corner of the machine as viewed in FIG. 1; and

FIG. 3 is a perspective view with the door members shown in open position.

The dominant features of our design reside in the portions shown in full lines.

The control arm for operating the door members of the disclosed dishwashing machine is U-shaped in form and is continuous around the rear portion thereof to said door members as shown. The rear of the machine is otherwise plain.

We claim:

The ornamental design for a commercial dishwashing machine, as shown and described.
